UNITED STATES PATENT OFFICE.

ERASMO DI SPIRITO, OF JERSEY CITY, NEW JERSEY, ASSIGNOR OF THIRTY-FIVE PER CENT TO EMILIO LUCCIOLA, OF JERSEY CITY, NEW JERSEY.

RAIL GUARD AND MEANS FOR APPLYING THE SAME.

Application filed November 5, 1925. Serial No. 67,146.

To all whom it may concern:

Be it known that I, ERASMO DI SPIRITO, a citizen of the United States of America, residing at Jersey City, in the county of

5 Hudson and State of New Jersey, have invented certain new and useful Improvements in Rail Guards and Means for Applying the Same, of which the following is a specification.

10 This invention relates to new and useful improvements in guard rails and means for applying the same.

The primary object of the invention is to provide a guard rail which may be quickly 15 and easily applied to a service rail without altering the construction of the latter in any respect.

A further object of the invention is to provide means for applying the guard rail which will permit of the latter being adjusted to compensate for wear.

A still further object of the invention is to provide improved means for adjusting a guard rail in respect to its associated serv- 25 ice rail.

Other objects and advantages of the invention will be apparent during the course of the following description.

In the accompanying drawings forming a 30 part of this specification and in which like numerals are employed to designate like parts throughout the same,

Figure 1 is a top plan view of the guard rail and its associated service rails, the 35 guard rail being constructed in accordance with this invention,

Figure 2 is a side elevational view of the structure shown in Fig. 1,

Figure 3 is a similar view to Fig. 2, but 40 taken on the opposite side of the structure,

Figure 4 is a fragmentary, longitudinal, horizontal view taken upon line IV—IV of Fig. 2,

Figure 5 is a vertical sectional view taken 45 upon line V—V of Fig. 2,

Figure 6 is a vertical sectional view taken upon line VI—VI of Fig. 2,

Figure 7 is a fragmentary elevational view, partly in section, showing the middle 50 portion of the guard rail structure,

Figure 8 is a detail perspective view of one type of adjusting wedge employed in the manner illustrated in the previously referred to figures,

55 Figure 9 is a detail perspective view of a

different form of adjusting wedge employed, and

Figure 10 is a detail perspective view of a rail brace block employed and clearly illustrated in operation in Figs. 6 and 7.

60

In the drawings, wherein for the purpose of illustration is shown a preferred embodiment of this invention, the numeral 5 designates the guard rail which has formed integrally therewith the plurality of tie plates 65 which will be given the separate reference numerals 6 to 11 inclusive. The tie plates

6 to 11 inclusive are braced in respect to the guard rail by the integral webs 12. Figures 1 to 3 inclusive and 7 clearly illustrate 70

the middle tie plates 8 and 9 as being united on the side of the guard rail 5 adjacent to the rail or rail ends 13 to form a seat 14 which functions to properly support the abutting ends of two rails, as clearly illustrated in Fig. 1, when the guard rail is applied to the service rail at a point where two rail ends are joined. Figs. 1, 4 and 5 clearly illustrate the tie plates 7 and 10 as extending 75

laterally beyond the ends of the remaining tie plate, i. e., beyond the far side of the service rail to a greater extent than do the remaining tie plates, for permitting the same to perform a function which will be 80

described at a later point.

85 It is to be understood, of course, that in adjusting the guard rail 5 in respect to the service rail 13 for taking up any wear that occurs, the tie plates 6 to 11 inclusive must necessarily be shifted longitudinally of their supporting ties, not shown.

In view of this fact, the ends of the respective tie plates are provided with an aperture 15 and an elongated slot 16. These apertures and slots are

intended to receive tie securing spikes, not 90 shown, which will be utilized in the following manner. In securing the guard rail to its supporting ties, securing spikes may be

driven in the slots 16 after which the guard rail is properly adjusted. To maintain the 95

guard rail in its adjusted position, additional securing spikes should then be driven through the apertures 15. It will now be apparent that when it becomes necessary to

adjust the guard rail in respect to the service rail for taking up wear in the former, the securing spikes should be removed from the apertures 15 while the spikes may be

retained in the slots 16 while the guard rail 100 is being adjusted. This will permit the

105

guard rail in its adjusted position, additional securing spikes should then be driven through the apertures 15. It will now be apparent that when it becomes necessary to

adjust the guard rail in respect to the service rail for taking up wear in the former, the securing spikes should be removed from the apertures 15 while the spikes may be

110

retained in the slots 16 while the guard rail is being adjusted. This will permit the

guard rail to be adjusted without placing the service rail out of service or operation at the location of the guard rail. After the guard rail is again adjusted, it only becomes necessary to drive spikes through the apertures 15 to again lock the guard rail in its adjusted position.

Figure 7 shows the middle portion of the guard rail 5, that is the portion in vertical alignment with the rail end seat 14, as having extending laterally inwardly from the tread and web portions thereof a wedge abutment 17 which is clearly illustrated in Fig. 1 as having its front face 18 beveled 10 in the direction of the length of the guard rail 5. The abutment 17 also has its wedge face 18 provided with a transversely extending key receiving groove 19. Positioned upon each side of the abutment 17 is a laterally projecting lug 20 which has its lower face suitably spaced in respect to the rail and seat 14 to permit the base flange of the respective rail ends to be received therebetween.

Figures 1, 6 and 9 illustrate a wedge member 21 as being located between the beveled face 18 of the abutment 17 and the adjacent sides of the service rails 13. This wedge 21 has its inner face 21^a beveled in 25 the opposite direction to the direction the face 18 of the abutment 17 is beveled, as clearly illustrated in Fig. 1, so that relative lateral movement of the wedge 21 in respect to the abutment 17 will cause pressure to be applied to the service rails to move the guard rail 5 laterally of the service rails 13. The wedge 21 is provided with a transversely extending key 22 which is formed with a plurality of apertures 23. These 30 apertures are intended to receive a cotter pin 24, best illustrated in Fig. 1, for the purpose of preventing movement of the wedge 21 in the direction for loosening the same or reducing the wedging action 35 between the abutment 17 and the adjacent service rail ends 13.

Figures 1, 4 and 5 illustrate the opposite ends of the guard rail 5 as having formed on the inner face of the same wedge abutments 25 and 26. These abutments function in the same manner as the abutment 17 and in respect to each other so that a brief description of the same is deemed to be all that is necessary. Each abutment 25 or 26 is provided with a beveled front face 27 which is engaged by the beveled face 28 of a wedge 29, of the type illustrated in detail in Fig. 8. Each abutment 25 or 26 is formed with a key receiving groove 30, as 40 illustrated in Figs. 4 and 5 which receives the key 31 of a wedge 29. This key is provided with a plurality of apertures 32 that are intended to receive a cotter pin 33 for preventing movement of the wedge 29 45 in a direction to loosen the same. Figure 5

clearly illustrates the bottom portion of each abutment 25 or 26 as having a groove or notch 34 cut therein to provide a space between its respective tie plate for permitting the adjacent base flange of the service rail 70 to be received therewithin.

So far there has been described means for adjusting the guard rail 5 and service rail ends 13 away from each other and it now becomes necessary to describe the means 75 employed for drawing the guard rail and service rail ends toward each other. This mechanism is clearly illustrated in Figs. 1, 2, 4 to 6 inclusive and 9.

Figures 1, 2 and 6 illustrate the service 80 rail end supporting seat 14 as having suitably joined thereto or formed integral therewith a yoke 35 which terminates in a perpendicularly extending head 36 having a bolt 37 adjustably threaded therethrough. 85 This bolt is provided with a suitable jam nut 38 and spring washer 39 which function to prevent loosening of the bolt. Operated upon by this bolt is a service rail bracing block 40 which is suitably notched at 41 90 to receive the tread of the service rail and is otherwise shaped to substantially correspond with the contour of the tread, web, and base flange of the said service rail. The outer edge of this block 40 is recessed at 42 95 for receiving the inner end of the bolt 37, see Fig. 5.

Figure 1, 2, 4 and 5 show the tie plates 7 and 10 as having mounted upon the ends, which were formerly referred to as extending beyond the ends of the remaining side plates, perpendicularly extending heads 43 which have bolts 37 adjustably threaded therethrough. These bolts are the same as described in connection with the structure 100 shown in Fig. 6 and have associated therewith a rail bracing block 40. Further description of this structure is, therefore, unnecessary.

It is to be understood that the form of 110 this invention herewith shown and described is to be taken as a preferred example of the same, and that various changes in the shape, size, and arrangement of parts may be resorted to without departing from the 115 spirit of the invention or the scope of the subjoined claims.

Having thus described the invention, I claim:

1. A guard rail having a plurality of 120 integral spaced tie plates, wedge abutments formed integral with the inner side of the guard rail, a wedge for each abutment which is movable to cause adjustment of the guard rail and service rail away from each other, 125 and means carried by the free ends of the tie plates for gradually adjusting the guard rail and service rail toward each other.

2. A guard rail having a plurality of 130 integral spaced tie plates, wedge abutments

formed integral with the inner side of the guard rail, a wedge movable to cause adjustment of the guard rail and service rail away from each other, means for preventing said wedges from loosening, and means carried by the free ends of the tie plates for gradually adjusting the guard rail and service rail toward each other.

3. A guard rail having a plurality of integral spaced tie plates, wedge abutments formed integral with the inner side of the guard rail, a wedge for each abutment which is movable to cause adjustment of the guard rail and service rail away from each other, means for preventing said wedges from loosening, a plurality of service rail bracing blocks located outwardly of the service rail, and means carried by the free ends of

the tie plates for adjusting said blocks toward the service rail.

4. A guard rail having a plurality of integral spaced tie plates, wedge abutments formed integral with the inner side of the guard rail and having transverse key receiving grooves, a wedge for each abutment which is movable to cause adjustment of the guard rail and service rail away from each other, a key having a longitudinal series of apertures formed integral with each wedge and receivable in its respective abutment groove, and pins selectively received in said apertures for preventing movement of the wedges which would loosen the same.

In testimony whereof I affix my signature,
ERASMO DI SPIRITO.
